[57] CLAIM

The ornamental design for a gun grip template, as shown and described.

DESCRIPTION

FIG. 1 is a view of the front side of the design and is a mirror opposite of the rear side thereof, the right, left, top and bottom sides of the design are flat and unornamented.

FIG. 2 is the exploded view of the front side of the design, the rear side being a mirror image; and,

FIG. 3 is a view of the set of grip components related to a pistol and is a mirror opposite of the other side.

The broken line showing of a pistol in FIG. 3 is for illustrative purposes only and forms no part of the claimed design.
